STOCKING

Oscar Walter Marden, Drexel Hill, Pa.

Application May 4, 1937, Serial No. 140,583

2 Claims. (Cl. 66—178)

My invention relates to a stocking and more particularly to a lady's stocking of the type made on flat machines and known as full-fashioned.

This type of stocking is either mis-named or not accurately named for the reason that it is not fully shaped or fashioned in the real sense of the word in that the shaping or fashioning, as shown by the fashioning marks in the conventional so called full-fashioned stockings extend for a space of three and one-half inches more or less along that portion of the stocking registering with the upper portion of the calf of the leg. These fashioning and narrowing marks, while serving somewhat to shape the calf portion of the stocking, are nevertheless not really effective in shaping the entire leg for the reason that they are placed and cover the area of the stocking which least needs fashioning, or shaping. In other words, the average calf of the average leg usually fits well within the average leg portion of a stocking, and the place which really needs fashioning or narrowing and which, by observation, will be seen to be the portion where a good fit is not now achieved, is between the heel top and the lower portion of the calf, or where the calf of the leg begins to narrow down to form the ankle. This portion of the stocking is not properly shaped or fashioned by the conventional narrowing now employed.

Furthermore, as will be seen if a conventional full-fashioned stocking is minutely examined either by means of an enlarged photograph or under a magnifying glass, the conventional narrowing marks exert a pull against the wales of the stocking which tends to dispose the wales at a relatively large, angle with respect to the vertical seam thus putting a strain on the wales and producing the visual effect of enlarging or fattening the calf which effect is undesirable except in the most exceptional cases of an exceptionally thin calf. Also, when a conventional full-fashioned stocking is worn it will be noted that the lower ends of the initially, substantially parallel rows of fashioning marks tend to diverge at about the point where the calf of the leg begins to taper downwardly, thereby producing the visual effect of a thick ankle. In order to insure a clear understanding I wish to explain that by "calf", as the term is used in the specification and claims, I intend to designate the portion of the leg where it begins to swell from a point below the knee until said portion begins to taper downwardly, and that by "ankle" I mean that portion of the leg which begins at the point where the calf begins to taper and until the leg begins to enlarge at a point slightly above the heel proper or the transversely projecting ankle bones. Furthermore, the tension that the narrowing points exert on the wales tends to weaken the structure and increase the hazard of runs particularly when the extremely sheer character of the stocking is taken into consideration. Another disadvantage in the full-fashioned stockings heretofore used is that the fashioning or narrowing points constitute relatively large and rough knobs or projections which tend to snag and catch and this is due to the fact that the entire number of needles, which are dropped in the narrowing of a stocking, are dropped according to conventional methods in the relatively limited space of about three and one-half inches, so that the proximity of the narrowing marks to each other, and the necessity of effecting all the narrowing within that short space, produces the effect referred to which really mars the appearance of the stocking rather than improves it. Indeed, the narrowing points could be placed closer to the selvedge and taken up in the seam when the stocking blank is sewed except for the fact that in that case a full-fashioned stocking could not be distinguished by the average purchaser from a seamless stocking provided with a mock seam. In other words, the fashioning marks are now positioned where they are primarily to indicate that the stocking is made on a flat machine or full-fashioned and not because the two substantially parallel three and one-half inch long rows of rough and relatively crude narrowing points are in themselves desirable.

It is therefore the object of my invention to produce a new stocking which is really full fashioned in the sense that it is fashioned from the point at which present narrowing points begin, at the top of the calf, all the way down to the lower end of the ankle or the top of the heel, thereby shaping or fashioning the stocking leg along its entire length and thus producing a better fit a better appearance and a stronger structure all over.

A still further object of my invention is to eliminate or substantially reduce the strain on the wales forming the portion of the stocking along which the narrowing points extend, not only to decrease the hazard of runs resulting from weakening of the wales, but also to permit the wales to extend substantially vertical up and down, or substantially parallel with the seam thus giving the thickened portion of the calf the visual effect of straightness and slightly ex-

aggerating its length thus giving the leg a most attractive appearance.

A clear understanding of the contrast I have tried to draw between the conventional stocking and the stocking made according to my invention could be had if two stockings, one made according to the conventional full-fashioned style and one according to my invention, which otherwise are identical, are mounted on identical artificial leg forms, or on a living model wearing one conventional full-fashioned stocking on one leg and, on the other leg, wearing a stocking made according to my invention.

In the accompanying drawing:

15 Fig. 1 represents a fragmentary side elevation of a full-fashioned stocking embodying my invention.

20 Fig. 2 represents a fragmentary rear elevation of the same showing more of the lower part of the stocking than is shown in Fig. 1.

25 Fig. 3 represents a diagrammatic and fragmentary rear elevation of a stocking blank embodying my invention before it is seamed.

30 Referring to the drawing in which like reference characters represent like parts, 1 designates the leg portion of a stocking which usually corresponds to the calf of a leg. 2 designates the ankle portion and 3 represents the top of the heel. 4 designates the seam. The parts so far described are conventional.

35 In conventional full-fashioned stockings the narrowing points 5 only extended from about the point designated A to approximately the point designated B and were disposed in two rows which were substantially parallel when the stocking was not worn on the leg but which diverged at their lower ends when the stocking was worn. Furthermore, all the needles that are dropped in the process of the narrowing of the stocking were dropped in conventional practice in approximately the space A—B. This resulted in excessive tension on the wales or courses which were, due to the pull exerted thereon, stretched taut at relatively great angles to the seam 4 and to the 40 narrowing points 5 themselves. This not only increased the hazard of runs due to strain, but also, the divergence of the wales with respect to the narrowing points together with the divergence of the lower portion of the narrowing points 5 themselves, gave the calf of the leg, as well as the ankle near the upper end of which the rows of narrowing points diverged, a rather flat or thickened appearance. Furthermore, the narrowing points confined in the space A—B only 45 shaped or fashioned the stocking along that general area and left the lower portion of the stocking entirely unfashioned and simply sewed or seamed into a tubular formation. According to my invention, instead of dropping the entire number of needles in the space A—B, I distribute the dropping of the needles along the space A—C, which, as will best be seen from Fig. 3, extends from the point at which the conventional narrowing marks begin (near the top of the calf) all the 50 way down to the top of the heel of the stocking. The lowermost four or five of the narrowing points are taken up in the seam 4 (see Fig. 2) when the stocking is sewed so that, in the finished product, the narrowing points are visible only 55 along the distance A—D. The gradual converging of the narrowing points from B to D as well as the shaping of the leg of the stocking by means of the invisible narrowing points between D and C gives the lower portion of the calf and the ankle 2 of the stocking a tapering and

well-rounded effect, while the diverging of the narrowing points from B to E gives the calf a rounded effect, and the converging of the points between E and A gives the calf the effect of tapering upwardly towards the knee which would be the perfect structure in a naturally well-formed leg. In addition to the visual effect produced by the disposition of the narrowing points as stated, it will be seen that the wales of knitting 6 between the narrowing points 5 and the 10 seam 4 are substantially parallel with the seam and that the wales 7 disposed outside of the narrowing points 5 are disposed at very small angles with respect to the seam 4 or the narrowing points 5. The practically vertically disposed 15 wales 6 also aid in giving the rear portion of the calf a graceful lengthened appearance, while the only slightly inclined wales 7 give the calf and the leg in general a well-turned effect. Furthermore, the disposition of the wales 6 vertically, 20 and of the wales 7 at only a very slight angle, greatly decreases tension or pull on the wales and hence adds to their durability and renders them less breakable than they would be otherwise. By dropping the narrowing needles available over 25 the entire distance A—C, the resulting narrowing points 5 are spread over double the conventional distance A—B and hence are smaller, smoother and less conspicuous. Since the narrowing points begin to converge downwardly 30 from about the point B to about the point C, it will be seen that the upper portion of the narrowing points, namely, from the point B to the point A, are substantially parallel with each other as well as with the selvedge edges 35 which ultimately are joined by the seam 4. While this is true of the stocking in its blank form, as seen in Fig. 3, the narrowing points from B to A assume a very slight arcuate form when the stocking is worn, but not enough to 40 destroy or alter their substantially parallel disposition as noted.

45 It will thus be seen that I have produced a new stocking which is really, and in the full sense of the word, fully shaped or fashioned, in that it is shaped from the top of the heel to the top of the calf, and that, by doing so, I have created a distinctly new and improved fit and appearance of the stocking, and greatly increased its strength and durability.

50 While in the drawing I have shown the narrowing marks or points as extending from the top of the heel to the present day conventional upper extremity of the leg, it is to be understood that my invention is not limited to this specific disclosure since a lesser or greater number of needles may be dropped, or the needles dropped may be spread over a longer or shorter extent, the principal feature of my invention being in converging the narrowing marks and extending them 55 as far as it is necessary to shape the ankle as well as the calf of the leg and in relieving the tension on the wales to lessen the danger of breakage, as well as to produce the desirable visual effect resulting from the less angular disposition of the 60 wales hereinabove described.

65 Having thus described my invention, what I claim as new and desire to secure by Letters Patent is:

70 1. As an article of manufacture a full-fashioned stocking blank having narrowing points extending along substantially the entire length of the leg portion thereof between the calf portion and the top of the heel portion, and in which the upper portion of the narrowing points which 75

extend along the calf portion are substantially parallel with the selvedge edges, and in which the remaining narrowing points which extend down to the top of the heel portion gradually converge towards their respective selvedge edges so that several of the lowermost of said narrowing points are taken up in the seam when said blank is formed into a stocking.

2. A full-fashioned stocking made from the blank defined in claim 1, wherein several of the narrowing points next above the top of the heel merge with the seam of said stocking.

OSCAR WALTER MARDEN.
